TOGGLE BOLT

Joseph H. Molat, New York, N. Y.

Application April 10, 1942, Serial No. 438,359

5 Claims. (Cl. 85—3)

This invention relates to toggle bolts and has for one of its objects the provision of an improved toggle bolt, which shall be constructed and arranged as to automatically accommodate itself to varying space conditions found within walls where it is desired to use toggle bolts.

Another object of my invention is to provide an improved toggle bolt which shall be characterized by the simplicity of its construction and by the simplicity of the manner of its use, and which at the same time shall be highly efficient in use and represent a general improvement in the art.

Other objects of my invention will in part be obvious and in part hereinafter pointed out.

The invention accordingly consists in the features of construction, combinations of elements, and arrangements of parts which will be exemplified in the construction hereinafter described and of which the scope of application will be indicated in the claims.

In the accompanying drawing, in which is shown various possible embodiments of this invention:

Fig. 1 is a vertical sectional view through a portion of a wall construction with a toggle bolt, constructed in accordance with my invention, attached thereto;

Fig. 2 is an elevational view of the toggle bolt shown in Fig. 1, but illustrating the manner of attaching the same in position;

Fig. 3 is a cross-sectional view taken substantially along the line 3—3 of Fig. 2;

Fig. 4 is a vertical sectional view of a portion of a wall construction, similar to Fig. 1, but showing the application of a modified form of my toggle bolt constructed in accordance with my invention; and

Fig. 5 is a perspective view of the Fig. 4 form of toggle bolt.

Referring now in detail to the drawing I have shown in Figs. 1 to 3 a toggle bolt 10 constructed and arranged in accordance with my invention and effectively positioned in a wall. For purposes of illustration I have shown a wall structure comprising a front wall 11, a rear wall 12 spaced therefrom and a cross support 14 of the customary materials employed in the art.

The toggle bolt of my invention comprises a frame 15 having a top wall 15a, side walls 15b and end walls 15c and 15d. Each of the side walls 15b is provided with longitudinal slotted openings 16. A block 17 is freely disposed within the channel of the frame 10 formed between the side walls 15b. The said block 17 is provided with project-

ing pins 18 on opposite sides thereof which are freely slidable in the openings 16, so that the block 17 is held captively attached to the frame 10 and is slidably movable in the direction of the longitudinal axis of the said frame. The movement of the said block 17 is limited by the end walls 16a and 16b of the slots 16. The block 17 is provided with a threaded opening 19 having its axis at right angles to the axes of the pins 18. Received in the opening 19 is the threaded shank 20a of a bolt 20 having the customary enlarged head 20b.

The top wall 15a of the frame 15 is provided with a slotted opening 21 and the end wall 15d is provided with a notch 22 extending upwardly from the bottom edge thereof. The purpose and function of the opening 21 and notch 22 will become apparent, in the following description of the manner of using the toggle bolt of my invention as above described. When it is desired to attach a member 27 to a wall, it is merely necessary to make an opening 25 in the outer wall 11 sufficiently large for the toggle bolt frame 15 to pass therethrough. The bolt 20 is first threadedly turned in the block 17 until the bolt shank 20a touches the wall 15c and the pins 18 abut the walls 16b of the slots 16. This will maintain the frame 15 in a position with its longitudinal axis parallel to the axis of the bolt 20 and in which position the frame is passed through the opening 25. After this the bolt is unscrewed from its former position to its dotted line position (Fig. 2) until the frame 15, due to gravity, will pivot about the pins 18 and will automatically drop to the dotted line vertical position with the shank 20a of the bolt freely passing through the slotted opening 21 in the wall 15a as shown in Fig. 2. While in the last named position of the frame 15, the bolt is screwed inwardly in the block 17 until the frame is held up against the inner surface of the wall 11 to hold the member 27 in place.

It is thus seen from the above described construction that the toggle bolt of my invention will automatically adjust itself to whatever space conditions are met within the walls. Thus, for example, in Fig. 1 I have shown a condition in which there is a cross beam 14 and for that reason it is noted that the frame 15 is in a higher vertical position with respect to the bolt 20 than that shown in Fig. 2 which represents a condition where no such obstruction as the member 14 is present.

In Figs. 4 and 5 I have shown a modified form of my invention in which, instead of the frame 15, I employ a simple flat plate of metal 30 or similar rigid material to which I attach a pair

of spaced flexible wire members 31 and 32. The said wires 31 and 32 may be attached to the plate 30 in any suitable manner known to the art, such as, for example, by providing holes in the plate 30 into which the wire ends are received and held in position by solder (see Fig. 4). The plate 30 is provided with a threaded through opening 35 disposed between the wires 31 and 32. With this form of my invention a hole 36 is first made in the outer wall 11 and the plate 30 passed therethrough by first flexing the wires 31 and 32 so that they will lie parallel to the longitudinal axis of the plate 30, as shown by the dotted lines 31' and 32' in Fig. 5 of the drawing. After insertion the plate 30 is restored to vertical position, and in abutting relation with the inner surface of the wall 11, as shown in Fig. 4, and with the wires 31 and 32 projecting through the opening 36. The plate 30 is thus held in position by pulling on the wires 31 and 32. While in such last named position the bolt 40 is threadedly passed through the plate opening 35 and the member 37 thus fastened in position. The wires 31 and 32 may then be clipped off, if desired, as in Fig. 4 or they may be left to project beyond the outer surface of the wall 11 to be utilized for hanging pictures or other articles thereon. In the latter case the member 37 may serve as a washer with openings to permit the wires 31 and 32 to pass therethrough.

If desired, instead of separate wire members 31 and 32, the said members 31 and 32 may be joined by a loop portion 38 (see Fig. 5) to provide a U-shaped member in which the free ends of the legs 31 and 32 are fastened to the plate 30.

It will thus be seen that there is provided a device in which the several objects of my invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention I claim as new and desire to secure by Letters Patent:

1. A toggle bolt comprising in combination a threaded bolt member, a rigid member threadedly received on said bolt, an abutment member pivotally mounted on said rigid member, said abutment member being at the same time slidably with respect to said rigid member so that the said abutment member may be slidably moved with respect to said bolt before the auto-

matic pivotal movement of said abutment member to accommodate itself to varying space conditions within wall structures.

2. A toggle bolt comprising in combination, a threaded bolt member, a rigid member threadedly received on said bolt, an abutment member comprising a top wall, a pair of side walls depending therefrom to form a channel space therebetween within which said rigid member is freely received, said side walls being provided with slotted openings and means for pivotally and slidably mounting said abutment member on said rigid member, said means comprising projections on opposite sides of said rigid member rotatably and slidably received in said slotted openings so that pivoting of said abutment member is possible at any point along said slotted opening.

3. A toggle bolt according to claim 2 in which said top wall of said abutment member is provided with a slotted opening through which a portion of the said bolt is adapted to freely project.

4. A toggle bolt according to claim 2 in which the said abutment member is provided with end walls, one of which has a notch therein extending upwardly from the bottom edge thereof into which the bolt is adapted to be received upon pivotal movement of said abutment member with respect to said rigid member.

5. A toggle bolt comprising in combination, a threaded bolt, a rigid member threadedly received on said bolt, an abutment member comprising a top wall, a pair of side walls depending therefrom to form a channel space therebetween within which said rigid member is freely disposed, end walls, each of said side walls, and said top wall being provided with relatively long slotted openings disposed substantially parallel to the longitudinal axis of said abutment member, means for pivotally and slidably mounting said abutment member on said rigid member, said means comprising projections on opposite sides of said rigid member rotatably and slidably received in said slotted openings of said side walls, said bolt being adapted to freely project through the said slotted opening in said top wall of said abutment member upon pivotal movement of said rigid member with respect thereto, one of said end walls being provided with a notch extending upwardly from the bottom free edge thereof into which the bolt is adapted to be received, the opposite end wall being adapted to serve as a stop member for the movement of the bolt member to maintain said abutment member in a position with its longitudinal axis substantially parallel to the axis of said bolt.

JOSEPH H. MOLAT.
